FLUID-DISPENSING APPARATUS

Charles M. Tursky, Philadelphia, Pa., assignor to
Service Station Equipment Company, Con-
shohocken, Pa., a corporation of Delaware

Application March 24, 1931. Serial No. 524,871

5 Claims. (Cl. 299—78)

My invention is applicable to apparatus for dispensing fluids to motor vehicles, and particularly for dispensation of compressed air for inflation of vehicle tires through a hose provided with a check valve fitting at its discharge end, which hose is normally retracted and wound on a reel by a spring device appurtenant to the reel but which hose is adapted to be withdrawn from the reel more or less during each dispensing operation. It is the practice of operators to let go of such hose after each dispensing operation and permit it to be automatically rewound by the action of the reel spring, and it is customary to provide the valve fitting at the end of the hose with a guard ring of rubber or similar resilient material back of it to minimize the shock of contact of said fitting with the casing or frame in which the reel is mounted for rotation. Such hose reel structures are of several types respectively adapted for suspension from ceilings or side walls and for erection upon floors or pavements, the latter being known as "curb stands."

The compressed air for such apparatus is ordinarily supplied by an electrically operative pump which is automatically set in operation either by the withdrawal of the hose from the reel or when the pressure of the air in a storage tank is reduced below a predetermined degree. In any case, the unauthorized use of such apparatus subjects the owner to loss and expense. Therefore, it is the object and effect of my invention to provide means to prevent the unauthorized use of such fluid dispensing apparatus including lockable means for sealing the discharge end of the hose.

As hereinafter described, such lockable means is embodied in a housing containing a spring pressed buffer device adapted to minimize the shock of impact of the valve fitting at the termination of each rewinding operation of the hose; which buffer device is more efficient and durable than the mere buffer ring on the hose and also serves to thrust the valve fitting out of seclusion into operative position when the lockable means aforesaid is released.

My invention includes the various novel features of construction and arrangement herein-after more definitely specified.

In said drawings; Fig. I is a front view of a convenient embodiment of my invention with the housing door open showing the front view of the buffer mechanism.

Fig. II is an elevation of the right hand side

of the structure shown in Fig. I, with the buffer mechanism retracted and the door locked.

Fig. III is a vertical sectional view of said structure, taken on the line III, III in Fig. I, in the direction of the arrows on said line.

Fig. IV is a fragmentary plan sectional view, taken on the line IV, IV in Fig. I.

In said figures; the hose 1 is provided with the check valve fitting 2 at its discharge end backed by the buffer ring 3 which when the hose is retracted by the spring reel device aforesaid bears upon the circular series of four buffer rollers 4. Said rollers 4 are conveniently formed of rubber and are independently journaled on respective shafts 5 which are mounted in the inwardly turned flanges 6 on the bearing frame plate 7 which is conveniently formed of pressed sheet metal and rigidly connected, conveniently by the two screws 8, with the buffer carriage 10 which is a cylindrical tubular ring mounted 75 to reciprocate between the three guide ribs 11 in the housing 12.

As shown in Fig. I, said housing 12 has a series of openings 13 for screws by which it may be attached to the frame or casing 14 in which the hose reel is mounted. Said ribs 11 are respectively formed on the three housing bars 15 which are in unitary relation with the spider plate 16 at their inner ends.

Said buffer carriage 10 has the spring plunger 17 rigidly connected therewith, as indicated in Fig. IV, and said plunger is mounted to reciprocate in the bearing bracket 19 on said plate 16 at the inner end of said housing 12. The spring 20 which encircles said plunger 17 bears at its outer end upon said carriage 10 and at its inner end upon said bracket 19 and tends to thrust said carriage outwardly in said housing, but such movement is limited by the cotter pin 21 which extends through said plunger 17 and is adapted to encounter the inner face of said bracket 19, as shown in Fig. IV, when said carriage is in its outermost position shown in Figs. III and IV.

Said housing 12 has the hinge lugs 22 in spaced relation supporting the pintle 23 which extends through the lug 24 on the door 25 which is thus hingedly connected with said housing. Said housing has the lock lug 27 which fits through the notch 28 in said door 25 when the latter is shut and has the opening 29 therethrough, best shown 105 in Fig. III, to receive the staple 30 of the padlock 31 when said door 25 is in closed position, as shown in Fig. II.

As shown in Fig. III, said buffer device normally presents the hose fitting 2 projecting from the 110

housing 12 so that it may be readily grasped by the operator who desires to dispense the fluid and, when the operator releases said hose after the dispensing operation, the impact of the buffer 5 3 when the hose 1 is withdrawn to the position shown in Fig. III is received by the spring pressed rollers 4 on the carriage 10 which yields to the right in Fig. III compressing the spring 20 to minimize the shock of stopping the movement of the reel. However, when the reel is stopped, said 10 buffer carriage recoils under pressure of the spring 20 to again present the fitting 2 in the position shown in Fig. III.

When it is desired to lock the device 15 aforesaid against unauthorized use, it is necessary for the operator to push the fitting 2 backward into the housing 12 in which it is secluded by closing the door 25 and locking it with said padlock 31, as shown in Fig. II.

I do not desire to limit myself to the precise 20 details of construction and arrangement herein set forth, as it is obvious that various modifications may be made therein without departing from the essential features of my invention, as defined 25 in the appended claims.

I claim:

1. In a fluid dispensing apparatus, the combination with a hose having a valve fitting at the discharge end thereof; of a housing for said hose; 30 resilient buffer means in said housing adapted to yieldingly stress said hose fitting toward the exterior of said housing, including a carriage mounted to reciprocate in said housing; buffer rollers mounted on said carriage, embracing said hose behind said fitting; a spring normally stressing said carriage and fitting toward the exterior of said housing; and means limiting the movement of said carriage by said spring.

2. In a fluid dispensing apparatus, the combination with a hose having a valve fitting at the discharge end thereof; of a housing for said hose; buffer means in said housing adapted to yieldingly stress said hose fitting toward the exterior of 80 said housing, including a carriage mounted to reciprocate in said housing; buffer rollers mounted on said carriage, embracing said hose behind said fitting; and a spring normally stressing said carriage and fitting toward the exterior of said housing.

3. In a fluid dispensing apparatus, the combination with a hose; of a housing for said hose; buffer means in said housing adapted to yieldingly stress said hose toward the exterior of said housing, including a carriage mounted to reciprocate in said housing; a spring normally stressing said carriage toward the exterior of said housing; and means limiting the movement of said carriage by said spring.

4. In a fluid dispensing apparatus, the combination with a hose; of a housing for said hose; buffer means in said housing adapted to yieldingly stress said hose toward the exterior of said housing, including a carriage mounted to reciprocate in said housing; and a spring normally stressing said carriage toward the exterior of said housing.

5. In a fluid dispensing apparatus, the combination with a hose; of a housing for said hose; buffer means in said housing adapted to yieldingly stress said hose toward the exterior of said housing, including a roller, and a spring normally stressing said roller toward the exterior of said housing.

CHARLES M. TURSKY.
